UNITED STATES PATENT OFFICE.

PAUL KLEMOFF, OF CHICAGO, ILLINOIS, ASSIGNOR TO GENERAL AMERICAN TANK CAR CORPORATION, OF CHICAGO, ILLINOIS, A CORPORATION OF WEST VIRGINIA.

HOPPER CAR.

Application filed March 26, 1926. Serial No. 97,658.

My invention relates more particularly to so-called hopper-cars, namely cars provided with hoppers to receive the material to be transported and having openings in their bottom portions controlled by doors through which the contents of the cars are dumped.

My objects, generally stated, are to provide a car the hopper of which shall present the maximum cubical capacity within the permissible limits of the outside dimensions of the car, while affording to the structure the desired resistance to the various stresses to which it is subjected in use; to so shape the walls of the hopper that a maximum cubical capacity is afforded and lodgment of the contents of the hopper, especially at the corners thereof, in the dumping of the hopper, is avoided, or in other words, the hopper is rendered quickly self-clearing while having a maximum cubical capacity; to provide an underframe for the car of such construction that while sufficiently resistant to the stresses to which it is subjected in use, the car may be equipped with standard draft-gear equipment without sacrificing the cubical capacity of the car or its necessary resistance to the stresses to which it is subjected in use; and other objects as will be manifest from the following description.

Referring to the accompanying drawings:

Figure 1 is a view in side elevation of a hopper car constructed in accordance with my invention. Figure 2 is a plan view thereof. Figure 3 is an enlarged view in longitudinal sectional elevation of one end of the car of the preceding figures, the section being taken at the line 3 on Fig. 2 and viewed in the direction of the arrow. Figure 4 is a section taken at the line 4—4 on Fig. 3 and viewed in the direction of the arrows. Figure 5 is a plan broken sectional view of the structure shown in Fig. 4, the section being taken at the lines A and B on Fig. 4 and viewed in the direction of the arrows and showing the shape of the sectioned parts at the planes of these lines, and showing by the dotted lines C and D the shape of the end and corner plates, at planes corresponding with the lines C and D on Fig. 4. Figure 6 is a plan sectional view taken at the line 6 on Fig. 3 and viewed in the direction of the arrow the coupler and

draft-gear mechanism being omitted. Figure 7 is a section taken at the irregular line 7—7 on Fig. 6 and viewed in the direction of the arrows. Figure 8 is a view of the car in end elevation, the view being taken at the line 8 on Fig. 1 and viewed in the direction of the arrow; and Figure 9, a perspective interior view of an end of the hopper, the side walls, bottom, and a portion of the end wall being shown by dotted lines.

The underframe of the car comprises structural steel channel side-girders 20 with their channels opening toward the center of the car, and structural steel beam-uprights 21 connected with the ends of the girders 20 and shown as of H-shape in cross section. The underframe also comprises hollow cast steel members 22 one at each corner of the underframe, connected at flanges 23 and 24 thereon with the adjacent uprights 21 and side-girders 20, the members 22 having hollow oppositely-extending extensions 25 and 26, which are disposed at an angle to the longitudinal axis of the car, as shown. The extensions 25 are located between, and secured to, structural steel arms 27 and diagonal beam-members 28 the arms 27 and members 28 being secured at their inner ends to hollow cast-steel connecting members 29 which in turn are connected with the side-girders 20. The extensions 26 are located between, and secured to, the inner ends of pressed steel members 30 and the members 28, the outer ends of the members 28 and 30 being spaced apart, as shown, at each side of the car and interfitting with, and secured to, web-portions 31 and 32 of cast-steel striking-members 33, one at each end of the car. The members 33 are connected at web-portions 34 and 35 thereof, midway between their ends, with the outer, overlapping ends of draft-sill structural steel channels 36 which latter are connected at their inner ends with cast-steel hollow members 37 forming continuations of the draft-sill channels 36 at each end of the car and open at their tops and bottoms, as represented at 38 and 39, respectively, to permit of the insertion therethrough of the door-operating devices hereinafter described.

Extending laterally of the members 37 are structural steel body-bolster members 40, their inner ends being connected with the sides of the members 37 and their outer

ends with the members 28 and 29. Located between the draft-sill structures at opposite ends of the car and the members 22 are pressed structural steel bridging plate-structures 41 which incline outwardly towards the ends of the car, as shown, and are connected at their inner flanged ends with the members 36 and 37 and at their outer flanged ends with the members 28 and 25.

10 The trucks 42 of the car, two being pivoted at each end thereof are pivoted, one to each of the members 22, as represented at 43, in a manner well known in the art.

Referring now to the structure mounted 15 on, and carried by, the underframe, it comprises the hopper for the material to be transported and represented generally at 44. The side walls of the hopper are represented at 45, each thereof being shown as formed of 20 sheets of steel presenting an upper section 46 and a lower section 47 secured together along lapped portions thereof one of which is deflected inwardly as shown. The upper sections 46 which are disposed substantially vertically are connected flatwise to the upper ends of the uprights 21 and are provided along their upper edges with rigid side bars 48 extending substantially the full length of the car and of general Z-shape as 25 shown (Fig. 4) and preferably so disposed that their web-portions 49 incline upwardly and outwardly at an angle of approximately 48° to a horizontal plane, the channels 50, formed by the webs 49 and the upper flanges 30 51 of these bars, containing angle-shaped 35 reinforcing fillets 52 riveted to these webs and flanges as shown; and the channels 53, formed by the webs 49 and the lower flanges 54 of these bars, containing angle-shaped 40 reinforcing fillets 55 riveted to these flanges and webs as shown. The upper edges of the plate sections 46 are inwardly turned to present flanges 56 which extend beneath, and flatwise oppose, the adjacent flanges 54 of 45 the Z-bars 48 and to which they are secured, the outer surfaces of the sections 46 being flush with the outer surfaces of the bars 48, as shown in Fig. 4.

The lower wall sections 47 incline downwardly and inwardly, as represented at 57, and terminate in depending flanges 58 which are reinforced by angle irons 59. Supported on the side girders 20 at intervals, and secured thereto, are upwardly extending angle-shape flanged gussets 60 against which the inclined portions 57 of the sheet sections 47 bear and to which, preferably, they are secured, the gussets 60 serving to reinforce and stiffen the sheet sections referred to, 55 against deformation, it being preferred that there be interposed between the side girders 20 and the members 60, and secured to both, plates 61 extending the full length of the side sheets at the lower end portions of the 60 latter, with their inner edges downwardly

inclined, as represented at 62, to be flatwise contacted with, and form supports for, the lower portions of the side sheets. As shown, stiffening members 63 are fitted at intervals into the spaces defined by the channels of 70 the side girders 20 and the plate 61 and are secured to these members.

To stiffen the lateral sides of the hopper, truss members 64 are provided substantially midway between the ends of these sides, 75 these members conformingly fitting the inner surfaces of the side walls 45 of the hopper and being secured thereto and to the Z-bars 48.

The end walls of the hopper, which incline downwardly and inwardly, are shown as each formed of a central flat sheet section 65; sheet sections 66 of the same shape and size disposed at opposite sides of the section 65 with adjacent edges overlapped 80 and secured together, the outer sides of the sections 66 inclining downwardly and inwardly as shown at 67; corner slope-sheets 68 at the outer edges of the sections 66 and secured thereto, and sheet sections 69 beyond 90 the sheets 68 and secured to the outer edges of the latter and to the adjacent inclined end edges 70 of the side sheets 45, the sheets 66, 68 and 69 at each corner of the hopper being preferably formed integrally from a 95 single sheet of metal. The sheets 65 and 66 are shown as extending in substantially parallel relation to each other to present a substantially continuous flat surface and are connected at their upper ends with rigid 100 stiffening end bars 71 shown as of angle-shape in cross section.

The slope sheets 68, in accordance with one feature of my invention, are so shaped 105 as to cause those portions of the contents of the hopper which are disposed at these corner-forming sheets to readily slide out of the lower discharge opening of the hopper in the emptying of the latter, while affording to the hopper the maximum cubical capacity. To this end each sheet 68 is so shaped, preferably by pressing the sheet from which it is preferably formed, that the sheet extends, at any plan section thereof, 110 at a less angle to the longitudinal axis, or median line, of the car, than at any plan section thereof below, as represented in the drawings particularly in Figs. 2, 3, 4, 5 and 9. In other words the sheet is twisted from 115 its upper edge progressively toward its lower edge in a direction toward parallelization of this sheet with the adjacent flat, transversely-disposed, section 66 adjacent thereto, thereby causing the section 68 to be substantially of the same form as a portion 120 of a convolution of a spiral, but in pressing the sheet to the form stated it is preferably so shaped that its upper and lower edges and its side edges are caused to be substantially straight and any transverse section 125

thereof is a substantially straight line, as indicated by the several lines of section in Fig. 5, certain of which are dotted lines.

The lower edges of the sheet sections 65, 5 66 and 68 are cut to extend straight and in substantially plan alignment as shown in Fig. 2, and reach to the adjacent ends of the side-wall sections 57 and connect with the bolster members 40; the sections 65, 66 and 10 68, with the sections 57, defining the discharge opening of the hopper, the end walls described being preferably provided with depending aprons 72 extending in a plane below the lower edges of the side walls 45 15 of the hopper.

The sheet sections 68 are preferably shaped as shown and each is provided, at its outer edge, with an upper and a lower flange 73 and 74, respectively, which lap the 20 inner and outer surfaces, respectively, of the adjacent side wall 45 at the end of the latter.

The end walls of the hopper are shown as braced to resist the stresses imposed 25 against them by the weight of the contents of the hopper, these bracing means comprising the uprights 21 against the upper ends of which portions of these end walls flatwise extend and to which they are secured; 30 upright 75 located at the ends of the car adjacent the corners thereof and rigidly connected with extensions 76 of the striking plates 33, the upper ends of these uprights being connected with gusset plates (not 35 shown) which are located at the undersides of the end walls of the hopper and are connected therewith; and uprights 77 connected with the striking plates 33 adjacent the center line of the car and connected at their 40 upper ends with gusset plates 78 which in turn flatwise oppose, and are connected with, the flanges of angle-irons 79 extending along, and secured to, the undersides of the end walls of the hopper at the joints between 45 the plate-sections 66 and 67. The end walls are further braced by angle-irons 80 connected with brackets 81 secured to the uprights 77 and connected at their inner ends with gussets 82 connected with the angle-irons 79 and also with uprights 83 rising 50 from, and connected with, the floor plate of the underframe.

The side and end walls of the hopper are rigidly connected together at their upper edge portions, to cause the hopper to present at its upper edge a rigid substantially rectangular frame, by angle-shaped corner pieces, or gusset-caps, 84, which overlap the adjacent end portions of the walls of the hopper at the corner portions thereof and the adjacent ends of the side and end bars 48 and 71.

The doors for the hopper are represented at 85, these doors being hingedly supported 65 at their outer, upper, edges to hinge-butts

86 secured to the plates 61 at intervals along the latter, as indicated at 87, to adapt them to be swung upwardly to the closed position shown in Fig. 4 and downwardly to open position. Any suitable mechanism for operating the doors may be provided, that shown being of common and well known form and comprising, generally stated, cranks 88 carried by shafts 89 journaled on the car at opposite ends of the latter and 70 connected together, at sprockets 90 thereon, by a sprocket-chain 91 and rotated by either one of the drive shafts 92 journaled on the car and having gears 93 meshing with gears 94 on the shafts 89, the cranks 88 being 75 pivotally connected at 89 with links 90 which in turn are connected at 91 with sectional link-devices 92 which extend through the upper and lower openings 38 and 39 in the members 37.

The connections between the various beams, sheets, girders and the like, described and forming the underframe, the superposed frame and the hopper, may be made in any suitable way, as for example by riveting, or 90 welding, them at their flatwise contacting portions, it being preferred that such parts described and shown as flatwise engaging, be so secured together at all of such portions.

By way of enumeration of certain of the advantages resulting from constructing a car in accordance with my invention, it may be stated, in general, that by so constructing the car, it affords the maximum hopper-capacity within the limit of the allowable dimensions; is self-clearing in dumping; is adapted for the use of standard couplers and draft gear, and may be constructed at the minimum cost. More specifically, certain 100 advantages are that the arrangement of the parts of the underframe, as shown and described, whereby the body bolsters, instead of occupying a position in which they register with the center line of the trucks as is common practice in cars of the kind to which my invention relates, are positioned substantially at the inner ends of the draft-sills and at the bottom of the end walls of the hopper, affords sufficient space for the installation of the standard form of coupler and draft-gear without reducing the size of the hopper. In this connection it may be 110 stated that by such arrangement of the parts of the underframe the load to which the side girders 20 are subjected is carried to the trucks 42 through the members 29, 27, 28 and 22; and the load imposed on the end walls of the hopper is transmitted to the bolster members 40 and thence through the 115 members 27 and 28 to the side girders 20 and eventually to the members 22.

Another advantage resulting from such arrangement of the parts of the underframe is that the car may be "jacked up" at its four 120 125 130

H-beams 21 without subjecting the under-frame to undue stresses, because of the provision of the members 41 forming bridges from the members 28 and 22 and the draft-sill structure.

The feature of providing the side girder members 48 as Z-bars arranged as stated is of great advantage as the hopper may be provided of the maximum capacity within 10 the dimension limits (which may not be exceeded in the building of cars) without impairing its rigidity and resistance to the stresses to which it is subjected in use.

The feature of providing the sheets forming 15 the corners of the hopper and involving the sheets 68 as described, is also of great advantage inasmuch as thereby the maximum capacity of the hopper is afforded; and by the action which results from 20 the material descending along these portions, all of the material at the corner-portions freely and quickly slides through the discharge opening in the hopper.

While I have illustrated and described a 25 particular construction of my invention, I do not wish to be understood as intending to limit it thereto, as the same may be variously modified and altered without departing 30 from the spirit of my invention.

What I claim as new, and desire to secure 35 by Letters Patent, is:

1. In a hopper-equipped car, the combination of its underframe and a hopper supported thereon, the upper edge-portion of 40 said hopper comprising stiffening bars of substantially Z-shape in cross-section extending lengthwise of the car.

2. In a hopper-equipped car, the combination of its underframe, and a hopper supported thereon, the upper edge-portion of 45 said hopper comprising stiffening bars of substantially Z-shape in cross-section extending lengthwise of the car, with their flanges extending angularly relative to a horizontal plane.

3. In a hopper-equipped car, the combination of its underframe, and a hopper supported thereon, the upper edge-portion of 50 said hopper comprising stiffening bars of substantially Z-shape in cross-section extending lengthwise of the car, with their flanges extending at an angle of approximately 48° to a horizontal plane.

4. In a hopper-equipped car, the combination of its underframe, and a hopper supported thereon, the upper edge-portion of 55 said hopper comprising stiffening bars of substantially Z-shape in cross-section extending lengthwise of the car along its upper edges, each of said bars being so disposed that its web extends obliquely upwardly and away from the center of the hopper.

5. In a hopper-equipped car, the combination of its underframe, a hopper sup-

ported thereon, the upper edge-portion of said hopper comprising stiffening bars of substantially Z-shape in cross-section extending lengthwise of the car, and re-enforcing fillets in the spaces provided between the webs and flanges thereof. 70

6. In a hopper-equipped car, the combination of its underframe, and a hopper supported thereon, the upper edge-portion of said hopper comprising stiffening bars of 75 substantially Z-shape in cross-section extending lengthwise of the car, and the side walls of said hopper having flanges at their upper edge-portions flatwise opposing, and secured to, the lower flanges of said bars. 80

7. In a hopper-equipped car, the combination of its underframe, and a hopper supported thereon, the upper edge-portion of said hopper comprising stiffening bars of substantially Z-shape in cross-section extending lengthwise of the car, with their flanges extending angularly relative to a horizontal plane, and the side walls of said hopper having flanges at their upper edge-portions flatwise opposing, and secured to, the lower flanges of said bars. 85

8. A hopper, the walls of which are disposed in a general rectangular arrangement, the inner surfaces of certain of said walls at the corners of the hopper extending progressively from their upper to their lower end-portions at an increasing angle to the median line of the car. 90

9. A hopper, the walls of which are disposed in a general rectangular arrangement, the inner surfaces of certain of said walls at the corners of the hopper extending progressively from their upper to their lower end portions at an increasing angle to the median line of the car, any transverse element in any one of said inner surfaces being substantially a straight line. 100

10. A hopper, the walls of which are disposed in a general rectangular arrangement and presenting a substantially rectangular discharge opening, certain of said opposed walls presenting flat wall portions between the corner portions of the hopper, flanked by corner-forming wall portions the inner surface of each of which latter extends progressively from its upper to its lower end portion, at an increasing angle to the median line of the car. 110

11. A hopper, the walls of which are disposed in a general rectangular arrangement and presenting a substantially rectangular discharge opening, certain of said opposed walls presenting flat wall portions between the corner portions of the hopper, flanked by corner-forming wall portions the inner surface of each of which latter extends progressively from its upper to its lower end portion, at an increasing angle to the median line of the car, the inner surface of each of said corner-forming wall portions 120

105

115

125

130

presenting a substantially plane surface at any plan section therethrough.

12. A hopper, the walls of which are disposed in a general rectangular arrangement, 5 the wall portions at the corners of the hopper being in the form of twisted sheets presenting substantially straight side edges, the inner surface of each of said sheets being a plane surface at any plan section there-
10 through.

13. A hopper, the walls of which are disposed in a general rectangular arrangement, the inner surfaces of certain of said walls at the corners of the hopper between their 15 marginal edges being of substantially the same contour as that presented by a sheet twisted to form a portion of a convolution of a spiral, said walls inclining downwardly toward the center of the car.

20 14. A hopper, the walls of which are disposed in a general rectangular arrangement, the inner surfaces of certain of said walls at the corners of the hopper between their marginal edges being of substantially the 25 same contour as that presented by a sheet twisted to form a portion of a convolution of a spiral, said walls inclining downwardly and inwardly toward the point of intersection of the longitudinal and transverse cen-
30 ter lines of the car.

15. In a hopper-car, the combination of an underframe, trucks supporting the underframe and a hopper on said underframe, said underframe being formed of side girders, 35 draft-sill structures at opposite ends of the car, bolsters adjacent the inner ends of said draft-sill structures, bearing-members for the trucks located between said bolsters and the extremities of said underframe, and
40 means connecting together said parts of the underframe.

16. In a hopper-car, the combination of an underframe, trucks supporting the underframe and a hopper on said underframe, said 45 underframe being formed of side girders, draft-sill structures at opposite ends of the car, bolsters adjacent the inner ends of said draft-sill structures, bearing-members for the trucks located between said bolsters and the extremities of said under-frame, and
50 means connecting together said parts of the underframe comprising members connected with said girders, bolsters, and bearing-
55 members and extending generally in the direction of the length of the car.

17. In a hopper-car, the combination of an underframe, trucks supporting the underframe and a hopper on said underframe, said underframe being formed of side girders, 60 draft-sill structures at opposite ends of the car, bolsters adjacent the inner ends of said draft-sill structures, bearing-members for the trucks located between said bolsters and the extremities of said underframe, and
65 means connecting together said parts of the

underframe comprising pairs of members at each end of the underframe connected with said girders, bolsters, and bearing-members and converging toward the ends of the car.

18. In a hopper car, the combination of an 70 underframe, trucks supporting the underframe and a hopper on said underframe, said underframe being formed of side girders, draft-sill structures at opposite ends of the car, bolsters adjacent the inner ends of said 75 draft-sill structures, bearing-members for the trucks located between said bolsters and the extremities of said underframe, means connecting together said parts of the underframe comprising members connected with said girders, bolsters, and bearing-members 80 and extending generally in the direction of the length of the car, and striking-members at the ends of the underframe connected with the outer ends of said second-named mem-
85 bers.

19. In a hopper-car, the combination of an underframe, trucks supporting the underframe and a hopper on said underframe, said under-frame being formed of side girders, 90 draft-sill structures at opposite ends of the car, bolsters adjacent the inner ends of said draft-sill structures, bearing-members for the trucks located between said bolsters and the extremities of said underframe, 95 means connecting together said parts of the underframe comprising pairs of members at each end of the under-frame connected with said girders, bolsters and bearing-members, and striking-members at the ends of the 100 under-frame connected with the outer ends of said second-named members.

20. In a hopper-car, the combination of an underframe, trucks supporting the underframe and a hopper on said underframe, said underframe being formed of side girders, 105 draft-sill structures at opposite ends of the car, bolsters adjacent the inner ends of said draft-sill structures, bearing-members for the trucks located between said bolsters and the extremities of said underframe, means connecting together said parts of the under-frame comprising members connected with said girders, bolsters, and bearing-members 110 and extending generally in the direction of the length of the car, and bridging members connected with said bearing-members and said draft-sill structure.

21. In a hopper-car, the combination of an underframe, trucks supporting the underframe and a hopper on said underframe, said underframe being formed of side girders, draft-sill structures at opposite ends of the car, bolsters adjacent the inner ends of said 120 draft-sill structures, bearing-members for the trucks located between said bolsters and the extremities of said underframe, means connecting together said parts of the underframe comprising pairs of members at each end of the underframe connected with
125

said girders, bolsters, and bearing-members and converging toward the ends of the car, and bridging-members connected with said bearing-members and said draft-sill structure.

22. In a hopper-car, the combination of an underframe, trucks supporting the underframe and a hopper on said underframe, said underframe being formed of side girders, draft-sill structures at opposite ends of the car, bolsters adjacent the inner ends of said draft-sill structures, bearing-members for the trucks located between said bolsters and the extremities of said underframe, means connecting together said parts of the underframe comprising members connected with said girders, bolsters, and bearing-members and extending generally in the direction of the length of the car, striking-members at the ends of the underframe connected with the outer ends of said second-named members, and bridging-members connected with said bearing-members and said draft-sill structures.

23. In a hopper-car, the combination of an underframe, trucks supporting the underframe and a hopper on said underframe, said underframe being formed of side girders, draft-sill structures at opposite ends of the car each comprising members aligned lengthwise of the car, bolster-members located at opposite sides of the inner members of said draft-sill structures, bearing-members for the trucks located between said bolsters and the extremities of said underframe, and means connecting together said parts of the underframe.

24. In a hopper-car, the combination of an underframe, trucks supporting the underframe and a hopper on said underframe, said underframe being formed of side girders, draft-sill structures at opposite ends of the car each comprising members aligned lengthwise of the car, bolster-members located at opposite sides of the inner members of said draft-sill structures, bearing-members for the trucks located between said bolsters and the extremities of said underframe, and means connecting together said parts of the underframe, comprising a pair of members at each end of the car connected with said girders, the outer ends of said bolster-members and with said bearing-members and converging toward the respective ends of the car.

25. In a hopper-car, the combination of an underframe, trucks supporting the underframe and a hopper on said underframe, said underframe being formed of side girders, draft-sill structures at opposite ends of the car each comprising members aligned lengthwise of the car, bolster-members located at opposite sides of the inner members of said draft-sill structures, bearing-members for the trucks located between said bolsters and

the extremities of said underframe, means connecting together said parts of the underframe comprising a pair of members at each end of the car connected with said girders, the outer ends of said bolster-members and with said bearing-members and converging toward the respective ends of the car and striking-plates located at the ends of the car and connected with the outer ends of said pairs of members.

26. In a hopper-car, the combination of an underframe, trucks supporting the underframe and a hopper on said underframe, said underframe being formed of side girders, draft-sill structures at opposite ends of the car, bolsters adjacent the inner ends of said draft-sill structures and at the bottoms of the end-walls of said hopper, bearing-members for the trucks located between said bolsters and the extremities of said underframe, and means connecting together said parts of the underframe.

27. In a hopper-car, the combination of an underframe, trucks supporting the underframe and a hopper on said underframe, said underframe being formed of side girders, draft-sill structures at opposite ends of the car, bolsters adjacent the inner ends of said draft-sill structures, uprights at the ends of said girders, bearing-members for the trucks located between said bolsters and the extremities of said underframe, and means connecting together said parts of the underframe.

28. In a hopper-car, the combination of an underframe, trucks supporting the underframe and a hopper on said underframe, said underframe being formed of side girders, draft-sill structures at opposite ends of the car, bolsters adjacent the inner ends of said draft-sill structures, uprights at the ends of said girders, bearing-members for the trucks located between said bolsters and the extremities of said underframe, and means connecting together said parts of the underframe, said uprights and bearing members being directly connected together.

29. In a hopper-car, the combination of an underframe, trucks supporting the underframe and a hopper on said underframe, said underframe being formed of side girders, draft-sill structures at opposite ends of the car, bolsters adjacent the inner ends of said draft-sill structures, uprights at the ends of said girders, bearing-members for the trucks located between said bolsters and the extremities of said underframe, and means connecting together said parts of the underframe, said uprights being directly connected with said girders and with said bearing-members.

30. In a hopper-car, the combination of an underframe, trucks supporting the underframe and a hopper on said underframe, said underframe being formed of side girders,

draft-sill structures at opposite ends of the car, bolsters adjacent the inner ends of said draft-sill structures, bearing-members for the trucks located between said bolsters and the extremities of said underframe, members connected with said girders and said bolsters, arms connecting said last-named members with said bearing-members and with said bolsters, arms connected with said bearing-members, and striking plates secured to the outer ends of said last-named arms.

31. In a hopper-car, the combination of an underframe, trucks supporting the underframe and a hopper on said underframe, said underframe being formed of side girders, draft-sill structures at opposite ends of the car, bolsters adjacent the inner ends of said draft-sill structures, bearing-members for the trucks located between said bolsters and the extremities of said underframe, members connected with said girders and said bolsters, arms connecting said last-named members with said bearing-members and with said bolsters, arms connected with said bearing-members, striking-plates secured to the outer ends of said last-named arms, and bridging members connected with said bearing members and with said draft-sill structures.

32. In a hopper-car, the combination of an underframe, trucks supporting the underframe, and a hopper on said underframe, said underframe being formed of side girders, uprights located at the ends of said girders, bearing-members for the trucks connected with said girders and said uprights, members located between said bearing-members at each side of the frame and secured to said girders, arms connecting said bearing-members with said second-named members, draft-sill structures at opposite ends of the car, bolster-members connected with said draft-sill structures at the rear ends thereof, and at the bottoms of the end-walls of said hopper, said bolster-members being located between the sets of bearing-members at opposite ends of the frame and secured at their outer ends to said second-named members, bridging-members connecting said bearing-members with said draft-sill structures, arms connected with said bearing members and extending therebeyond toward the ends of the car, and striking-plates at opposite ends of the car connected with the outer ends of said second-named arms.

PAUL KLEMOFF.
